NOAH R. WHITE Inventor.

By Richard P. Duren Attorney

UNITED STATES PATENT OFFICE.

NOAH R. WHITE, OF DELTA, COLORADO.

AUTOMATIC LUBRICATING DEVICE.

Application filed February 9, 1922. Serial No. 535,316.

To all whom it may concern:

Be it known that I, NOAH R. WHITE, a citizen of the United States, residing at Delta, in the county of Delta and State of Colorado, have invented certain new and useful Improvements in Automatic Lubricating Devices, of which the following is a specification.

This invention relates to new and useful improvements in lubricating devices of the force feed type.

An important object of the invention is to provide a device of this nature which can be readily applied to threshing machines to lubricate those bearings which have been found to "burn out" very rapidly from lack of proper lubrication.

A further object of the invention is to provide a lubricating device which is entirely automatic in its operation, thereby dispensing with the necessity of watching the various bearings to see that they receive the proper amount of lubrication.

Other objects and advantages of the invention will become apparent during the course of the following description.

In the accompanying drawings forming a part of the description and wherein like numerals are employed to designate like parts throughout the several views;

Figure 1 is a side elevation of the device shown applied to a threshing machine,

Figure 2 is an end elevation of the device.

Figure 3 is a bottom plan of one end of the device illustrating the means for imparting movement to the followers.

Figure 4 is a vertical section of the follower mechanism; and

Figure 5 is a perspective view of a part of the follower mechanism.

Referring now more particularly to the drawings wherein for the purpose of illustration is shown the preferred embodiment of my invention, the numeral 6 designates a portion of the casing of a threshing machine, which has mounted transversely therethrough a shaft 7 which operates the clover huller. This shaft is mounted in bearings 8 located at each side of the thresher casing. Inasmuch as the follower mechanism for each bearing 8 is substantially of the same construction, a description of one will suffice for all.

Rising from each bearing 8 is a lubricator feed pipe 9, the upper end of which sup-

ports a lubricant container or cup 10, the exterior surface of which is screw threaded, as clearly seen in Figure 2. In order that the lubricant or grease may be forced from the container 10 into the feed pipe 9 and then to the bearings, a follower cap 11 is screw threaded for cooperation with the lubricant cup 10 and when screwed down upon the cup, forces the grease from the receptacle into the feed pipe 9. To the top of this cap is secured a diametrically extending bar 12, having an aperture at each end thereof for the reception of a pair of legs 13 of a follower operating member.

This operating member is of substantially U-shaped configuration, the bridging portion 14 of which is offset laterally of the legs 13 in order that the legs may be passed down through a pair of apertures provided in a ratchet disk or wheel 15 and the bridging portion 14 of the operating member will avoid an anti-friction washer 16 disposed between the top of the disk and a supporting bar 17. This supporting bar 17 extends transversely of the threshing machine in spaced relation to the top thereof and is arranged substantially above the clover hulling drum inside of the casing. In order that the ratchet disks 15 may be rotatably mounted upon the under side of the supporting bar 17, a bolt 18 is passed through each end of the supporting bar and is extended through the adjacent ratchet disk and its cooperating washer 16. As seen in the drawings, ratchet teeth 19 of one disk depend from the under side thereof for a purpose which will presently be described. It is to be understood that the legs 13 of the follower operating members are to be spaced a substantial distance apart and sufficient to permit the vertical movement of these members without contacting with the ends of the supporting bar 17 when it is desired to remove the follower caps for refilling the lubricator cups 10.

As best seen in Figures 1 and 2, the supporting bar 17 is supported above the threshing machine by means of a bridge construction 20 rising from the top of the threshing machine. A bracket 21 is secured by its upper end adjacent one end of the supporting bar 17, as clearly shown in Figure 2, and is of substantially L-shaped configuration whereby the vertical arm thereof will be disposed in a vertical plane to one side of

the threshing machine. The lower end of this bracket is secured to the side of the threshing machine casing and a ratchet wheel 22 having peripheral teeth is mounted 5 upon the vertical arm of the bracket by means of a small shaft 23. The inner end of this shaft is equipped with a crank 24, upon which is mounted the dog 25. This dog is mounted upon the crank intermediate 10 of its ends and one end of the dog is weighted, while the opposite end is curved slightly upwardly for engagement and cooperation with the ratchet teeth 19 of one of the ratchet disk 15. It will be noted that only 15 one of the disks 15 is provided with ratchet teeth, for means which will be later described are provided for operating one of the disks from the other. In order to prevent the backward rotation of the disk 15 20 a pawl 26 is pivoted between its ends and has one of its ends weighted so that its opposite end will be normally retained against the teeth of the disk 15. This pawl 26 is pivoted to the vertical arm of the 25 bracket 21 directly beneath the pivotal connection of the dog 25 therewith. A pawl 27 is pivoted to the bracket 21 directly above the ratchet wheel 22 so as to cooperate with the ratchet wheel in preventing accidental 30 reverse rotation of the same.

Movement to the ratchet wheel 22 is imparted by means of an elongated rod 28, having its lower end pivotally connected as at 29 to a lateral extension 30 of an adjustable collar 31 fastened onto the extended end of straw rack shaft 32. Due to this specific construction, an eccentric connection is established between the collar 31 and the pitman rod 28. The opposite end of the 40 rod 28 is provided with a ratchet engaging member 33 which is of a resilient character, yet of sufficient strength to cause spasmodic rotation of the ratchet wheel 22. It will thus be seen that the upper end of the pitman rests upon the relative upper portion of the ratchet wheel 22 so that the ratchet engaging member 33 can slide over the ratchet teeth during downward movement of the pitman, and so that the element 33 45 can act upon the ratchet wheel to cause movement thereof during the upward movement of the pitman rod 28. This member 33 is formed with a pair of fingers 35 which straddle the ratchet 22 for preventing accidental 50 displacement of the member 33 from the ratchet. 55

A chain tightener sheaf 36 as shown in Figure 3 is provided to engage the idle run of the chain 34 to retain it in proper engagement with the disk wheels 15.

In order that the lubricating devices on opposite sides of the threshing machine may be operated simultaneously, the periphery of each disk 15 is equipped with sprocket 60 teeth adapted to cooperate with a sprocket

chain 34. Consequently, operation of one disk 15 will cause corresponding rotation of the other.

From the foregoing description, it will be seen that when the straw rack shaft 32 70 is put into operation, the pitman 28 works back and forth and causes step by step or spasmodic rotation of the ratchet wheel 22. Inasmuch as the crank 24 of the shaft upon which the ratchet wheel 22 is mounted is 75 caused to turn and carries the pawl 25, it will be seen that the disk 15 having the ratchet teeth will be caused to intermittently revolve. As the legs 13 of the follower operating members extend through the disks 80 15, they are caused to rotate and they consequently impart corresponding movement to the follower caps 11. Obviously, the grease contained in the follower caps and the cups 10 will be forced through the feed 85 pipe 9 and then through the bearings of the clover huller shaft 7. As it will be clearly understood from the description, the disks 15 are only caused to move a slight distance, possibly a fraction of an inch, each time the 90 dog 25 acts upon the ratchet disk 15 and therefore, it will be seen that the movement of the followers 11 is likewise very slight, and in fact, so slight that it will take practically half of a day of continuous operation 95 of the threshing machine before the follower caps have been driven to their lowermost position upon the lubricating cups 10. When the followers reach the limit of their downward movement, they automatically become disengaged from the follower operating elements 13 and consequently there will be no possibility of any of the parts breaking due to continual operation of the device.

After the follower elements 11 have become disengaged from their operating members, it is then known that it is time to refill the caps of the lubricating cups and this is accomplished by first lifting the follower operating members 13 sufficiently to permit 100 the followers 11 to be screwed off of the cups 10. After the caps have been refilled, the followers are then slightly screwed upon the cups and the follower operating members 105 properly assembled with the followers 11 so that the machine will again be ready for operation.

The foregoing description and the accompanying drawings have reference to the preferred or approved embodiments of my invention. It is to be understood however, that such changes may be made in construction and arrangement of parts, materials, dimensions, etc., as may prove expedient and fall within the scope of the appended claims.

Having thus described and illustrated my invention, what I now claim as new and desire to secure by Letters Patent is:

1. An automatic force feed lubricator comprising a lubricant receptacle, a cap fol- 130

lower associated therewith for ejecting lubricant therefrom, a rotary member having a pair of apertures, said follower having a pair of spaced apertures, and a removable U-shaped follower operating member having its arms extended through the spaced apertures in said rotatable member and said follower.

2. An automatic force feed lubricator comprising a lubricant receptacle, a cap follower associated therewith for ejecting lubricant therefrom, said follower having a pair of spaced apertures, a support, a rotary member mounted thereon, and having a pair of spaced apertures, a U-shaped removable follower operating member having its arms depending and extending through the apertures of the rotary member and said follower, and the bridging portion of said U-shaped follower operating member being off-

set laterally to avoid abutment with said support when the follower operating member is removed from its apertures in the rotary member and follower.

3. The combination with a shaft having a pair of bearings, a lubricant receptacle associated with each bearing, a follower threadedly engaged therewith for ejecting lubricant from the receptacle, a supporting bar arranged above the shaft, a pair of sprockets depending from said bar, an endless chain associated with said sprockets, means for driving one of said sprockets, and a follower operating member carried by each sprocket and adapted to be associated with said followers for automatically operating the same.

In testimony whereof I affix my signature.

NOAH R. WHITE.
